(57) **CLAIM**

We claim the ornamental design for a charging station for electric vehicles, as shown and described.

DESCRIPTION

FIG. 1 is a front, right and top perspective view of a charging station for electric vehicles showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of an encircled portion 9 of FIG. 1; and,

FIG. 10 is an enlarged view of an encircled portion 10 of FIG. 2.

The broken lines depict portions of the charging station for electric vehicles in which the design is embodied that form no part of the claimed design.

1 Claim, 10 Drawing Sheets
